UNITED STATES PATENT OFFICE.

AUGUST SCHNEELOCH OF SYRACUSE, NEW YORK, ASSIGNOR TO E. C. STEARNS & CO., OF SYRACUSE, NEW YORK, A CORPORATION OF NEW YORK.

LINE-LOCKING MECHANISM.

No. 852,400.

Specification of Letters Patent.

Patented April 30, 1907.

Original application filed May 9, 1902, Serial No. 106,524. Divided and this application filed October 9, 1902. Serial No. 126,600.

To all whom it may concern:

Be it known that I, AUGUST SCHNEELOCH, a citizen of the United States, residing at Syracuse, in the county of Onondaga and State of New York, have invented certain new and useful Improvements in Line-Locking Mechanism; and I do hereby declare the following to be a full, clear, and exact description of the invention, such as will enable others skilled in the art to which it appertains to make and use the same.

My invention relates to the line locking mechanism of a typewriting machine, by which the carriage may be automatically locked at any desired point, the operator is previously warned thereof, and the keys are also locked when the carriage is stopped.

This application is a division of my application filed May 9th, 1902, Serial No. 106,524.

20 My invention will be understood by reference to the drawing herewith, in which the reference numerals and letters of the specification indicate the corresponding parts in all the figures.

25 Figure I is a vertical section of the parts of my invention showing their arrangement in a typewriting machine. Fig. II is a vertical cross section on section line II of Fig. I, showing my invention in rear elevation.

30 Fig. III is a top plan of a portion of the line locking mechanism. Fig. IV is a cross section on line IV, IV, of Fig. III.

In the figures, 1 indicates the main frame of the machine, 29 the front bar carrying 35 rollers 27, 13 the rear grooved run-way for the carriage, 2 one of the key levers, 7 the key lever bracket, 12 the link thereon connected by intermediate link y, connected to type-bar 3, hung on suitable hangers 190, 40 secured on segment 188 by screws 191.

45 24 indicates the carriage side pieces, carrying the carriage front bar 26, and 28 the rear bar of the carriage frame groove 4 to engage with the balls 23.

40 are carriage brackets in which is journaled the platen rod 45, on which are fixed the swinging arms 41, carrying the platen holder and platen 186.

37 is the spring barrel and 98 a gear thereon 50 engaging with the carriage rack 128.

The front bar 26 of the carriage frame is provided with the groove 72 and rack 73, a top piece 74 is also provided with a corresponding groove 75, to which are fitted the sliding

pieces 76 and 77. On sliding piece 77 is 55 hung pawl 78, and it is also provided with the spring dog 79, held in engagement with rack 73 by its spring and provided with a thumb piece for releasing it therefrom, so that said sliding piece may be locked to the rack 73 60 at any desired point; 90 90 are stop pins for limiting the stroke of the swinging pawl 78; sliding piece 76 is also provided with a similar spring pawl 79, spring and thumb piece, whereby it may be locked in any desired position, and carries swinging stop 81, limited in its stroke by means of pin 83, engaging in its slotted end whereby a slight movement is obtained preventing a sudden jar or rebounding thereof when it engages with 70 abutment 88 on lever 80. Said stop 81 is to engage with abutment 88 and limit the movement of the carriage when it is moved back to the left. Said lever 80 is journaled at 85, and provided with two cam surfaces 75 86, 87, and abutment 88. Pawl 78 engages with cam face 86, pressing the lever downwardly and ringing the bell, then travels over the straight face and engages with cam 87, locking the key bars and immediately 80 stopping the carriage by engagement with abutment 88, by means of the mechanism to be described.

At its outer end lever 80 is connected by connecting bar 89 to one end of the bell lever 85 92, journaled to the frame by screw 93, and carrying on its lower arm the pivoted dog 94, so adjusted that, as connecting arm is raised, it will engage with a pin 105 on the outer end of the bell-hammer lever 95, journaled at 90 97, rock it against the force of the spring 96, and then release it, ringing the bell u; this is effected by the engagement of the pawl 78 with the cam surface 86. To the lower arm of bell lever 92 is pivotally connected sliding 95 lever 63, so that when pawl 78 engages with cam surface 87, connecting rod 89 is further raised, and pin 62 on sliding lever 63 is moved forward to engage with the tail 64, pivotally supported on extension 65 at 66, 100 and there held in position by spring 71, limited in its movement by lug 91 which is integral with the tail 64. This extension is secured on rod 68 journaled in the frame, and carrying the locking levers 67, supporting 105 locking rod 70 for engagement with key lever catches 69, and held back by a weaker spring 102.

To print more letters after the key levers are locked and the carriage is stopped; it is necessary to draw sliding lever 63 farther out by means of releasing button 103, whereby the lower end of bell lever 92 is drawn farther forward and abutment 88 depressed, so that cam 78 can ride over it and drop down on the other side; this is permitted by the arrangement of the tail 64, which snaps over the pin 62 into normal position, and the spring 102 throws locking rod 70 out of engagement with notches 69, unlocking the keys and permitting one or more characters to be written after the keys have been unlocked; the releasing button is released when spring *n* restores the parts to their normal position.

I do not limit myself to the construction here described, as the mechanism and arrangement of parts may be varied.

Having thus described my invention, what I claim as new and desire to secure by Letters Patent, is:

1. In a typewriting machine, the combination with the frame and the carriage, of a front bar and top piece on the carriage correspondingly grooved, a front carriage rack, an adjustable sliding piece fitted to said grooves, a spring dog connected to the sliding piece and adapted to engage with the rack, a swinging pawl on the sliding piece, a cam surface lever pivotally supported on the front of the machine having cam surfaces to engage with the swinging pawl, and means from the lever to ring the bell; and means from the lever to lock the keys, said means being operated by the engagement of the pawl with the cam surfaces.

2. In a typewriting machine, the combination with the frame and the carriage, of an adjustable swinging pawl arranged on the front of the carriage, a cam surface lever journaled on the front of the frame at about its center and having a cam surface on its inner end, a bar connected to the outer end of said lever, a bell-crank lever suitably journaled on the frame and connected to said bar, a pivoted dog on said bell-crank lever, a bell, a bell hammer lever, a spring to draw the bell hammer lever against the bell, and a pin to engage with said pivoted dog, whereby the bell hammer lever is rocked away from the bell and released.

3. In a typewriting machine, the combination with the frame and the carriage thereon, of an adjustable swinging pawl arranged on the front of the carriage, a cam surface lever journaled on the front of the frame at about its center and having a cam surface on its inner end, with which surface the pawl engages and the lever is rocked, a downwardly extending bar connected to the outer end of said lever, a bell-crank lever suitably journaled on the frame and having its upper arm connected to the lower end of said down-

wardly extending lever, a pivoted dog on the lower end of said bell-crank lever, a bell, a bell hammer lever, a spring to draw the bell hammer against the bell, and a pin to engage with said pivoted dog, whereby the bell hammer lever is rocked away from the bell and released.

4. In a typewriting machine, the combination with the frame and the carriage, of a front bar and top piece on the carriage correspondingly grooved, a front carriage rack, an adjustable sliding piece fitted to said grooves, a spring dog connected to the sliding piece and adapted to engage with the rack, a swinging pawl on said sliding piece, stops to limit the movement of the pawl, a cam surface rocking lever pivotally supported on the front of the machine having two cam surfaces to engage with the swinging pawl, whereby the lever is rocked, connections from the end of the lever to ring the bell operated by the rocking of the lever caused by the engagement of the pawl with the first cam surface, and means connected to the lever to lock the keys, said means being operated by the engagement of the pawl with the second cam surface.

5. In a typewriting machine, the combination with the frame and the carriage, of an adjustable swinging pawl supported on the carriage, a cam surface lever pivotally supported on the frame at about its center and having a cam surface on its inner end adapted to engage with the pawl as the carriage moves, a downwardly extending bar connected to the outer end of the lever, a bell-crank lever connected to the lower end of said bar and journaled on the frame, a sliding lever connected to the lower arm of said bell-crank lever, key lever catches, a locking rod suitably journaled and adapted to engage with said catches, a spring to hold said rod out of engagement and a projection on the sliding rod to engage with said locking rod and rock it into engagement with the key lever catches.

6. In a typewriting machine, the combination with the frame and the carriage, of an adjustable pawl arranged on the front of the carriage, a cam surface lever pivotally supported on the front of the machine having two cam surfaces on its inner end adapted to engage with the pawl as the carriage moves, a downwardly extending bar connected to the outer end of the lever, a bell-crank lever pivotally supported on the frame and having its upper arm connected to said bar, a sliding bar connected to the lower arm of said bell-crank lever, key lever catches, a locking rod frame suitably journaled, a locking rod thereon to engage with said key lever catches, a spring to hold said locking rod out of engagement, a tail pivotally connected to the said locking rod frame, a stronger spring to hold said tail in normal position, and a pin on the

sliding lever to engage with said tail and rock the locking rod into engagement with the key lever catches.

7. In a typewriting machine, the combination with the frame and the carriage, of an adjustable swinging pawl arranged on the front of the carriage, a cam surface lever pivotally supported on the front of the machine having two cam surfaces adapted to engage with the pawl as the carriage moves, an abutment on said lever a downwardly extending bar connected to the outer end of the lever, a bell-crank lever pivotally supported on the frame and having its upper arm connected to said bar, a sliding lever connected to the lower arm of said bell-crank lever, key lever catches, a locking rod frame suitably journaled, a locking rod thereon to engage with said key lever catches, a spring to hold said locking rod out of engagement, a tail pivotally connected to the said locking rod frame, a stronger spring to hold said tail in normal position, a pin on the sliding lever to engage with said tail and rock the locking rod into engagement with the key lever catches, a releasing button on the sliding rod to draw it out by hand to depress the abutment, and a spring to return the cam surface lever to normal position.

8. In a typewriting machine, the combination with the frame and the carriage, of a pawl on the carriage, a cam surface lever pivotally supported on the front of the machine and adapted to engage with said pawl, a sliding bar, connections from said sliding bar to said cam surface lever, a releasing pin on the sliding lever, a rock rod journaled in the front of the machine, lever arms thereon, a locking rod supported on said arms, key lever catches on the key levers, to engage with said locking rod, a spring to hold said locking rod out of engagement with said key lever catches, an extension on said rock rod, a tail pivotally supported on said extension, a stronger spring to hold said tail in normal position, and an extension on the sliding rod to engage with the tail and rock the locking rod into engagement with the spring catches.

9. In a typewriting machine, the combination with the frame and the carriage, of an adjustable sliding piece arranged on the front of the carriage frame, means to lock the sliding piece in the position in which it is adjusted, a depending pawl on the sliding piece, a rocking lever journaled on the frame and having two cam surfaces adapted to engage successively with the pawl as the carriage moves, a depending connecting bar connected to one end of the lever, a lever pivotally supported on the machine and connected to said connecting bar to ring the bell operated by

the rocking of the lever by the engagement of the pawl with the first cam surface and connections from the lever to lock the keys operated by the engagement of the pawl with the second cam surface.

65

10. In a line locking mechanism of a typewriting machine the combination with the frame and carriage, of a sliding piece on the carriage, a loose pawl on the sliding piece, a cam surface lever journaled on the frame in the path of the pawl, having a two cam surfaces to engage with the pawl and rock the lever, a connecting bar connected to one end of the lever, a bell lever pivotally supported on the machine and connected to the lower end of the connecting bar, said bell lever being operated by the first cam surface, a locking lever to lock the keys operated by the engagement of the pawl with the second cam surface, and connections between the bell lever and the locking lever.

11. In the line locking mechanism of a typewriting machine, the combination with the frame and carriage, of a sliding piece on the carriage, stops in the sliding piece, a pawl hung on the sliding piece between the stops, a cam surface lever journaled on the frame in the path of the pawl, having two cam surfaces to engage with the pawl and rock the lever, a depending connecting bar, a bell crank lever pivotally supported on the lower portion of the machine and connected to the end of the connecting bar to ring the bell, said bell ringing being operated by the first cam surface, a locking lever to lock the keys operated by the engagement of the pawl with the second cam surface, and connections between said lever and the bell lever.

12. In a typewriting machine, the combination with the frame and the carriage, of a sliding piece on the front of the carriage, a depending swinging pawl arranged on the sliding piece, a rocking lever journaled on the frame and having two cam surfaces at its inner end adapted to engage successively with the pawl as the carriage moves, a depending bar connected to the outer end of said lever, means for ringing the bell connected to the lower end of said bar and operated by the rocking of the lever by the engagement of the pawl with the first cam surface, and means to lock the keys also connected to the lower end of said bar and operated by the engagement of the pawl with the second cam surface.

In testimony whereof I affix my signature in presence of two witnesses.

AUGUST SCHNEELOCH.
